UNITED STATES PATENT OFFICE.

EDWARD B. STEWART AND WESLEY F. LELAND, OF ELGIN, ILLINOIS, ASSIGNOR TO THE WESTERN CASKET HARDWARE COMPANY, OF ELGIN, ILLINOIS, A CORPORATION OF ILLINOIS.

DESIGN FOR A COFFIN HANDLE.

Application filed April 5, 1922. Serial No. 1,541. Term of patent 3½ years.

To all whom it may concern:

Be it known that we, EDWARD B. STEWART and WESLEY F. LELAND, citizens of the United States, residing at Elgin, in the county of Kane and State of Illinois, have invented a new, original, and ornamental Design for Coffin Handles, of which the following is a specification, reference being had to the accompanying drawing, forming part thereof, wherein:

Figure 1 is a front elevation of the handle; Figure 2 is an end elevation of the handle. We claim:

The ornamental design for a coffin handle, as shown.

EDWARD B. STEWART,
WESLEY F. LELAND.
